DESIGN FOR A FLOOR OIL CLOTH.

ROBERT HOSKIN, OF BROOKLYN, NEW YORK, ASSIGNOR TO EDWARD C. SAMPSON, OF NEW YORK CITY.

Design No. 2,515, dated December 4, 1866.

SPECIFICATION.

TO ALL WHOM IT MAY CONCERN:

Be it known that I, ROBERT HOSKIN, city of Brooklyn, county of Kings, and State of New York, have invented or produced a new, original, and ornamental Design or Pattern for Floor Oil Cloths, carpets, and other fabrics; and I do hereby declare that the accompanying pattern or drawing marked and designated as Oak Pattern No. 1, which pattern fully represents said design, and is sufficient, without further aid, to enable any person skilled in the art to which it appertains to repeat it for practical use.

The colors, and the arrangement of them, may in the use of this design be varied to suit the views or fancy of the user or manufacturer.

What I claim as my invention, and desire to secure by Letters Patent, is—

The design or pattern for floor cloths, carpets, or other fabrics, as shown and described.

ROBERT HOSKIN.
